ATTORNEY:

UNITED STATES PATENT OFFICE.

THEODORE W. FOSTER, OF PROVIDENCE, RHODE ISLAND.

BRACELET.

No. 824,074.

Specification of Letters Patent.

Patented June 19, 1906.

Application filed January 6, 1906, Serial No. 294,935.

To all whom it may concern:

Be it known that I, THEODORE W. FOSTER, a citizen of the United States, residing at Providence, in the county of Providence and 5 State of Rhode Island, have invented a new and useful Improvement in Bracelets, of which the following is a specification.

This invention has reference to an improvement in bracelets, and more particularly to 10 an improvement in concealed hinges for bracelets.

The object of my invention is to improve- 15 the construction of a concealed hinge for bracelets, whereby the construction of the hinge is simplified and the cost of manufac- turing the same reduced.

A further object of my invention is to pro- 20 vide a bracelet with a strong and durable concealed hinge having a limited opening movement.

My invention consists in the peculiar and 25 novel construction of a concealed hinge for bracelets, with details of construction, as will be more fully set forth hereinafter.

Figure 1 is a side view of a bracelet pro- 30 vided with my improved concealed hinge and showing the bracelet in the closed position in full lines and in the open position in broken lines. Fig. 2 is an enlarged detail sectional 35 view of the hinge end of the bracelet looking at the outside face of the hinge. Fig. 3 is an enlarged detail sectional view taken on line 3 of Fig. 2 and showing the hinge in the closed position. Fig. 4 is an enlarged detail sec- 40 tional view similar to Fig. 3, showing the hinge in the open position. Fig. 5 is an enlarged detail edge view of one of the hinge members, and Fig. 6 is an enlarged detail view of the other member of the hinge look- 45 ing at the inner face of the same.

In the drawings, *d* indicates one semi-oval half, *e* the other semi-oval half, and *f* the im- 50 proved concealed hinge of the bracelet. The semi-oval halves *d* and *e* are constructed from a tube which is oval in cross-section. The half *d* has the end *d'* for the hinge *f* and the end *d''*. The half *e* has the end *e'* for the hinge *f* and the end *e''*. The ends *d'* and *e'* and the ends *d''* and *e''* coincide when the bracelet is closed. 55 The ends *d''* and *e''* may be provided with any one of the well-known forms of catches adapt- ed to hold the ends together when the bracelet is closed.

My improved concealed hinge *f* consists of 55 a solid member *g* and a tubular member *h*. These members *g* and *h* are curved to con-

form to the contour of the bracelet and shaped to fit in the ends *d'* and *e'* of the halves *d* and *e*. The member *g* of the hinge is constructed to have a solid body portion *g'*, from one end 60 of which extends a central arm *g''*, having a curved portion *g''*, merging into a hook-shaped end *g''''*, as shown in Fig. 5. The inner con- 65 cave face *g''''* and the outer convex face *g''''* of the curved portion *g''* is struck from a center which is concentric with the center on which the hinge opens, as shown in Fig. 4. The tubular member *h* has a hollow body portion 70 *h'*, an open end *h''*, and a closed end *h''''*, in which is a rectangular opening *h''''* the width of which coincides with the width of the central arm *g''* on the member *g'*, and a trans- 75 verse stop-pin *h''''*, which extends through holes adjacent the closed end of the member *h* across the opening *h''''*, as shown in Figs. 2 and 6, where it is secured by upsetting the 80 ends of the pin in the member or by other means. The side edges *h''''* *h''''* of the opening *h''''* in the member *h* are adapted to bear on the sides of the arm *g''* on the member *g*, the outer edge *h''''* of the opening on the inner concave face *g''''* of the arm *g''*, and the inner edge *h''''* of the opening on the outer convex face *g''''* of the arm *g''*, as shown in Figs. 2, 3, and 4.

The hinge is assembled by placing the central arm *g''* on the member *g* in the opening *h''''* in the member *h* in a position for the sides *h''''* *h''''* of the opening to engage with the sides of the arm *g''*, the edge *h''''* of the opening to engage with the inner concave face *g''''* of the arm and for the edge *h''''* of the opening to engage with the outer convex face *g''''* of the arm. The pin *h''''* is now driven through the holes in the member *h* over the concave face *g''''* of the arm *g''* and secured in the member *h*. The members *g* and *h* of the hinge are now forced into the ends *d'* and *e'* of the bracelet into a position where the center on which the hinge opens coincides with the juncture of the ends *d'* and *e'* of the bracelet. The body portions *g'* and *h'* of the hinge members are now se- 100 cured in the ends *d'* and *e'* of the bracelet by solder or other means. When the bracelet is closed, a space is formed between the stop- 105 pin *h''''* and the hook-shaped end *g''''* of the arm *g''*, as shown in Fig. 3, which allows for a pre- determined opening movement of the bracelet, and this opening movement of the bracelet is limited by the hook-shaped end *g''''* on the arm *g''* engaging with the stop-pin *h''''* on the member *h*, as shown in Fig. 4. The stop- 110 pin *h''''*, engaging with the hook-shaped end

g^4 , also prevents the separation of the hinge members after the same have been assembled.

Having thus described my invention, I claim as new and desire to secure by Letters Patent—

1. In a bracelet, a concealed hinge comprising a member having a solid body portion from one end of which extends a central arm having a curved portion merging into a hook-shaped end, the inner concave face and the outer convex face of the curved portion being struck from a center which is concentric with the center on which the hinge opens, and a tubular member having a hollow body portion, an open end, a closed end in which is a rectangular opening into which the central arm of the solid hinge member extends, and a stop-pin which extends across the inner concave face of the central arm on the solid member and is secured in the tubular member.
2. A concealed bracelet-hinge comprising a member g having a solid body portion g' from one end of which extends a central arm g^2 having a curved portion g^3 merging into a hook-shaped end g^4 , the inner concave face g^5 and the outer convex face g^6 of the curved portion g^3 being struck from a center which is concentric with the center on which the hinge opens, and a tubular member h having a hollow body portion h' , an open end h^2 , a closed end h^3 in which is a rectangular open-

ing h^4 formed by the side edges $h^6 h^6$, the edge h^7 and the edge h^8 , a stop-pin h^5 which extends across the inner concave face of the central arm g^2 and is secured in the tubular member h .

3. The combination with a tubular half d having the end d' and a tubular half e having the end e' of a bracelet, of a concealed hinge f composed of the members g and h , the member g having a solid body portion g' from one end of which extends a central arm g^2 , having a curved portion g^3 merging into a hook-shaped end g^4 , the inner concave face g^5 and the outer convex face g^6 of the curved portion g^3 being struck from a center which is concentric with the center on which the hinge opens, and the tubular member h having a hollow body portion h' , an open end h^2 , a closed end h^3 in which is a rectangular opening h^4 formed by the side edges $h^6 h^6$, the edge h^7 and the edge h^8 , a stop-pin h^5 which extends across the inner concave face g^5 of the central arm g^2 and is secured in the tubular member h , and means for securing the members g and h of the hinge in the ends d' and e' of the bracelet, as described.

In testimony whereof I have signed my name to this specification in the presence of two subscribing witnesses.

THEODORE W. FOSTER.
